FIG. 6.

FIG. 7.

INVENTOR.
GEORGE CLAUSING,
BY *Paulsen* *Paulsen*,
ATTORNEYS.

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed November 24, 1923. Serial No. 676,690.

To all whom it may concern:

Be it known that I, GEORGE CLAUSING, a citizen of the United States, residing at Portsmouth, in the county of Scioto and State of Ohio, have invented certain new and useful Improvements in Lasts, of which the following is a specification, reference being had therein to the accompanying drawings.

10 My invention relates to lasts.

It is the object of my invention to provide a last consisting of a toe and heel portion hinged to one another so that the respective portions will remain in either their collapsed or extended positions due to the resilient character of the medium of which the last is made.

It is a further object of my invention to provide a last in which the parts will have a fixed relationship to one another and also in which the parts of the last constitute the pivotal connection or joint between the two parts.

It is my object to provide means of connecting the two parts to one another of such a character that said connecting means will pass over a dead center when the last halves are moved from closed to extended position or vice versa.

30 In particular, it is my object to provide a last with a collapsible toe part which will act as a yielding member for maintaining the toe and heel parts in their respective positions.

35 Referring to the drawings:

Fig. 1 is a side elevation of the completed last in expanded position.

Fig. 2 is a section through the last in a similar position.

40 Fig. 3 shows the toe portion of the last when in collapsed position illustrating how the flexible tongue of the last is brought nearer the sole portion of the last when the last is in collapsed position.

45 Fig. 4 is a plan view of the last.

Fig. 5 is a bottom plan view of the last.

Fig. 6 is a section on the line 6—6 of Fig. 1 looking towards the rear of the last.

50 Fig. 7 is a section on the same line looking towards the toe of the last.

Referring to the drawings in detail:

The last consists of a heel portion 1 of suitable configuration. This heel portion has a forwardly and downwardly tapering

surface 2 which terminates at 3 in a semi-circular projection 4, constituting one portion of the joint between the last. Below this semicircular portion 4, which has a relatively flat top 5, is a vertical portion 6.

The rear face of the toe portion of the last, which portion is designated 7, has a similar vertical face 8, a concave portion 9, and an extended tapering aperture 10, which extends from the joint adjacent the hinge of the last to a point adjacent the toe as 65 at 11. The toe is designated 12.

For the purpose of description, the lower portion of the toe part of the last is designated 13 and known as the sole portion, while the upper part of the last, which is separated from the sole portion, is designated 14 and is known as the tongue.

The rear portion of the tongue is vertical as at 15, so that its face together with the face 2 forms the walls of a substantially triangular gap between the heel and toe portion of the last to permit of the collapsing of the last parts.

In order to hold the last halves together about the hinge there are provided a pair of links. These links are designated 16 and consist of a cup shaped middle portion 17 and flattened eyes 18. This gives strength to the links while it is easier to drill the holes 19 for the reception of the pins 20 and 21 which are respectively located in the toe and heel portions of the last. These links are mounted on the pins 20 and 21. The toe and heel portions are allowed some freedom of movement about the hinge with respect to the links or link by reason of the cutaway portions 22 and 23 in the respective halves of the last, said cutaway portions communicating with one another.

In the upper tongue portion of the toe part of the last is provided an aperture 24 for the reception of the end of the pin 25 which is carried by the heel portion. The margin of the opening 24 is surrounded by a metal washer 26 to give strength to that part of the last upon which considerable strain is placed and to take up any wear. A similar washer 27 is provided in the heel portion of the last.

When the last is collapsed the faces 15 and 2 will be brought adjacent to one another and the area 10 will be decreased because the pin 25 will serve to move the

tongue portion closer to the toe portion part of the last. The link 16 will pass over the dead center.

It will be observed that it is customary to 5 make such lasts of wood which have a certain resiliency so that this arrangement permits of the last being collapsed or expanded and the last remaining in either position 10 firmly without further care on the part of the operator.

The link swings freely in the cutaway portion in the halves of the last. The pins upon which the link is mounted may be inserted in any desired fashion through each 15 last half.

It will be understood that I do not desire to confine myself to the details of my construction, but comprehend within the scope 20 of my claims changes of material, and the like, and changes of construction.

Having thus fully described my invention, what I claim as new and desire to secure by Letters Patent, is:—

1. In a last, a toe portion, a heel portion, 25 a hinge therebetween, a link connecting said portions to one another about said hinge, said toe portion of the last being substantially divided into two parts adapted to be brought yieldingly towards one another, 30 means separate from the hinge and link carried by the heel portion of the last adapted to engage the yielding portion of the toe part of the last in sliding engagement therewith, there being means in said toe portion 35 of the last to accommodate and engage said first mentioned means, whereby when the last is collapsed the respective parts of the toe portion will be brought adjacent to one another and when the last is expanded said 40 respective parts will be moved from one another.

2. In a last, a toe portion, a heel portion, 45 a hinge therebetween, a link connecting said

portions to one another about said hinge, 45 said toe portion of the last being substantially divided into two parts adapted to be brought yieldingly towards one another, a pin carried by the heel portion of the last adapted to be inserted in the yielding portion 50 of the toe part of the last in sliding engagement therewith, said toe portion of the last being formed to accommodate said pin, whereby when the last is collapsed the respective parts of the toe portion will be brought adjacent to one another and when 55 the last is expanded said respective parts will be moved from one another, a washer carried by the heel portion of the last adjacent 60 said pin, and another washer carried by the toe portion of the last adjacent said pin.

3. In a last, a heel portion and a toe portion, each of said portions having a cutaway portion, a semicircular projection on the heel portion engaging with a semicircular concavity in the toe portion to form a joint, a vertical face on both the toe and heel portions beneath said joint, a vertical face on the toe portion above said joint, a spaced rearwardly upwardly extending face 70 on the heel portion above the joint, a link connecting said heel and toe portions located in the cutaway portion in said last, pins in each portion of said last for supporting said link, and means carried by the heel portion for engaging with a part of the toe portion, said part of the toe portion being adapted to yieldingly collapse and return to its expanded position when the last is collapsed or expanded, said link consisting of a pair of members having bodies arcuate in cross section and flattened ends with eyes 75 in said ends for mounting upon said pins.

In testimony whereof, I affix my signature.

GEORGE CLAUSING.
